(57) **CLAIM**

The ornamental design for a coffee dripper holder, as shown and described.

DESCRIPTION

1. Coffee dripper holder

1.1 : Top Perspective

1.2 : Bottom Perspective

1.3 : Front

1.4 : Back

1.5 : Top

1.6 : Bottom

1.7 : Left

1.8 : Right

1.9 : Rotated top view

1.10 : Cross-sectional view taken along 1.10-1.10 Fig. 1.5

1.11 : Cross-sectional view taken along 1.11-1.11 of Fig. 1.9

1.12 : Exploded

1.13 : Perspective view, shown in a state of use.

Thin lines on the surface shown in each of the drawings represent the shape of the surface in three dimensions; reproduction 1.13 shows the part which is not part of the claimed design by means of dotted lines.

1 Claim, 13 Drawing Sheets
